SHEET METAL WIRE CLAMP

Robert A. Becker, Sr., and Stephen P. Becker,
Poughkeepsie, N. Y.

Application January 14, 1935, Serial No. 1,712

3 Claims. (Cl. 24—125)

This invention relates to a sheet metal wire clamp of that class which is employed for securing two or more wires together or securing a lead wire to a feed wire in electrical installations and 5 the like, and the invention relates more particularly to the construction of a clamp from a sheet metal stamping.

While there have been many clamps designed for this purpose, they have been constructed in 10 the main from castings, bar stock and forgings, which has made them expensive on account of the material and the labor required in machining and assembling.

The object of the present invention is to provide 15 a clamp of this kind that shall be cheap, durable and efficient and readily installed or applied to the wire.

Another object of the invention is to provide an 20 article of this kind that shall be fabricated from sheet metal in the form of a stamping.

Another object of the invention is to provide an 25 article containing few parts and those of rugged design, combining strength with light weight.

Another object of the invention being to provide 30 a clamp that may be placed upon one wire during the operation of inserting the other wires which are to be clamped together.

With these and other objects in view, our invention 35 consists in certain novel construction and combination of parts as will hereinafter be fully described and claimed and further illustrated in the accompanying drawing which forms a part hereof and in which like figures of reference refer to corresponding parts in all of the views, and it is to be understood that slight changes may be made without departing from the spirit of the invention.

In the drawing:

Figure 1 shows an enlarged front elevation of a 40 sheet metal wire clamp embodying our invention.

Figure 2 is a top plan view of the same.

Figure 3 is a side elevation of the same.

Figure 4 shows a top plan view of the sheet 45 metal stamping before the same has been formed into the finished shape.

Figure 5 shows an elevation or a modified form of the clamp in which the hooked arms are integral with the back in place of being integral with the head as in Figures 1 to 4.

Figure 6 shows a side elevation of the same.

Figure 7 shows a top plan view of the stamping before the same has been formed into final shape.

Figure 8 is a front elevation of a similar form of 50 clamp but which is provided with interchangeable

and detachable shoes for supporting and clamping the wires.

Figure 9 is a cross sectional view of Figure 8, taken on the line 9—9 to illustrate the shoes.

Figure 10 is a side elevation of Figure 8. 5

Referring to the drawing, while we have herewith shown our clamp as being stamped from thin sheet metal, and primarily for use in connection with wires of small diameter, it is to be understood that by increasing the thickness of 10 the material from which it is punched, that the clamp may be made in larger sizes, and for use with more than two wires, and also that in place of the wire opening in the hooks, as shown, that these may be V-shaped or of other design, and 15 also that the shoes may be so designed as to be interchangeable for wires of different diameter, thus providing that the same clamp may be used for different wires by interchanging the shoes.

In Figures 1 to 4 inclusive, we have shown a 20 clamp that is punched or stamped from sheet material into a blank as shown in Figure 4, the inner edges of the hooks or arms 10 to be bent along the dotted lines 11 to form the flanges 12 which not only stiffen these arms 10 but also provide a wider edge upon which the wire 14 can rest.

The head 13 which is integral with the arms 10 is formed with a central hole 15 around which the metal is thickened by drawing or embossing the metal, and this hole 15 is threaded for the 30 clamping set screw 16. The arms 10 being bent at right angles to the head and in parallel relation with each other, the junction between the arm 10 and the head 13 being formed with a web 17 to add to the strength and rigidity of the device. 35

In the modified form illustrated in Figures 5, 6 and 7, the blank shown in Figure 7, is formed with a head 18, a back 19 and the two arms 20 which have their sides integral with the back 40 19.

In this form, the hooked arms 20 are also flanged as at 21, and the back 19 is provided with a rib 22, while the head 18 is also thickened by a boss 23. But in this case the flanges 21 are 45 shown on the outer sides of the arms 20.

As shown in Figure 8, the flanges have been omitted and the device is provided with the upper and lower interchangeable shoes 24 and 25; the lower shoe 25 bridging the arms 26 and curved 50 on its outer surface to conform to the curve of the hook of the arm, and upon its inner face to receive the wire; the edges being notched as at 27 to embrace the arms 26; the natural spring of the metal retaining this shoe in place. 55

5 The upper shoe 24 is also formed on its lower surface to take the wire 14, and has the notches 28 adapted to ride upon the arms 26; or these notches may be omitted and the shoe mounted between the adjacent edges of the hook as in the case of this upper shoe 24 it can not get away as it is secured to the end of the clamping screw 29, by a pair of lugs 30 that are struck from the shoe 24 and engage with an annular groove 31 10 formed adjacent the end of the screw 29.

15 In the employment of the clamp and especially where it is to be attached to an overhead wire, this may be done by the lineman with the use of one hand only and in the following manner.

15 The clamping screw having been backed off until a clear opening is obtained passed the point of the hooks, the clamp is hooked over the exposed overhead wire, where it will hang by itself, and the other wire or wires are then inserted and 20 the screw set up by the fingers until brought into contact with the wires to retain them until the screw is tightened by the use of a tool or other means.

25 Such an installation is not possible with clamps containing loose parts that have to be inserted and attached after the wires are in place.

If it is desired to attach a lead wire to the clamp, this can be done by gripping the end of the same under the jam nut or by some other 30 suitable means.

Having thus described our invention, what we claim as new and desire to secure by Letters Patent, is:

35 1. A wire clamp formed of a single sheet of metal and comprising a centrally located head having a threaded hole therein, a pair of parallel arms integral with said head and bent at

right angles thereto and formed with wire retaining openings, a clamping screw threaded through the hole in said head, a shoe mounted in said arms adjacent the lower ends thereof for increasing the contact surface with a wire, and a second shoe swivelly mounted on the end of the clamping screw and within the wire retaining openings in said arms and adapted to be brought into clamping contact with the wire by said screw.

2. A wire clamp comprising a pair of parallel hooks of sheet material, a head integral with the upper ends thereof and formed with a tapped hole for a clamping bolt, a flanged shoe formed with notches adapted to embrace the inner edges 15 of said hooks and retain said hooks in parallel relation and afford a large wire contact surface, and a second flanged follower having notches adapted to slide upon the inner edges of the hooks and formed with a swivel connection with 20 the clamping bolt.

3. In a sheet metal clamp of the class described, the combination with a single piece of sheet material formed with a head, a pair of parallel arms and a back connected to the head 25 by a web, said head thickened and provided with a threaded hole, a concave flanged shoe formed with guide notches adapted to be mounted within said arms to provide an enlarged surface for a wire, a second flanged and concave 30 follower slidably mounted on said arms and adapted to be clamped upon the wire, and a screw threaded within the thickened head for forcing the follower against the wire held in the shoe.
